[57] CLAIM

The ornamental design for a wall mounted flag case, substantially as shown and described.

DESCRIPTION

FIG. 1 is a front elevational view of a wall mounted flag case showing my new design;

FIG. 2 is a rear elevational view thereof;

FIG. 3 is a top plan view thereof.

FIG. 4 is a bottom plan view thereof.

FIG. 5 is a right side elevational view thereof, the left side being substantially identical thereto.
